(57) **CLAIM**

The ornamental design for buckle with tool surfaces, as shown and described.

DESCRIPTION

FIG. 1 is a front side elevation view of my new design for a buckle with tool surfaces.

FIG. 2 is a right side elevation view of FIG. 1.

FIG. 3 is a left side elevation view of FIG. 1.

FIG. 4 is a top side plan view of FIG. 1.

FIG. 5 is a bottom side plan view of FIG. 1.

FIG. 6 is a back side elevation view of FIG. 1; and,

FIG. 7 is a front perspective view of FIG. 1.

The features shown in broken lines in the drawing depict environmental subject matter only and form no part of the claimed design.
